UNITED STATES PATENT OFFICE

CHARLES WESLEY JONES, OF GLEN RIDGE, NEW JERSEY, ASSIGNOR TO SONS-CUNNINGHAM REED & RATTAN CO., INC., OF NEW YORK, N. Y., A CORPORATION OF NEW YORK

DESIGN FOR A CHAIR OR SIMILAR ARTICLE

Application filed June 9, 1931. Serial No. 40,143. Term of patent 7 years.

To all whom it may concern:

Be it known that I, CHARLES WESLEY JONES, a citizen of the United States, residing at Glen Ridge, in the county of Essex and State of New Jersey, have invented a new, original, and ornamental Design for a Chair or Similar Article, of which the following is a specification, reference being had to the accompanying drawing, forming part thereof.

The drawing shows in perspective a chair embodying my new design, it being understood that the design, shown in full lines, is repeated, as indicated, by dotted lines, at the other end of the chair, or similar article.

I claim:

The ornamental design for a chair or similar article, as shown and described.

In witness whereof, I have hereunto set my hand.

CHARLES WESLEY JONES.
